UNITED STATES PATENT OFFICE.

SHELDON B. BEACH, OF MERIDEN, CONNECTICUT, ASSIGNOR TO THE BRISTOL BRASS COMPANY, OF BRISTOL, CONNECTICUT, A CORPORATION OF CONNECTICUT.

DESIGN FOR A HAND-MIRROR OR SIMILAR ARTICLE.

40,472.

Specification for Design. Patented Jan. 25, 1910.

Application filed November 1, 1909. Serial No. 525,831. Term of patent 7 years.

To all whom it may concern:

Be it known that I, SHELDON B. BEACH, a citizen of the United States, residing at Meriden, in the county of New Haven and State of Connecticut, have invented and produced a new and original Design for a Hand-Mirror or Similar Article, of which the following is a specification.

The design has been illustrated in the accompanying drawings, in which—

The generic feature of the new and original design consists in the particular configuration of roses and scrolls which are grouped and interwoven to produce a harmonious and artistic result.

Having described my invention, I claim:

The ornamental design for a hand mirror or similar article as herein shown and described.

SHELDON B. BEACH.
